卷五

JOSEPH HEIDEMANN,

BY Oliver D. Ranger,
his ATTORNEY

UNITED STATES PATENT OFFICE

JOSEPH HEIDEMANN, OF LOS ANGELES, CALIFORNIA

GAME

Application filed September 8, 1930, Serial No. 480,374, and in Mexico September 12, 1929.

This invention relates to devices, though to some extent automatic, making it nevertheless possible by a handling with a certain amount of skill to function in a certain manner.

One of the objects of this invention is to provide a device in which a releasing member sets an operating member free to be caught by the operator by which in turn the releasing member can be set free to be again used by the operator.

Another object is to provide automatic catching means for the releasing member by which this member is held in the device in case that the operator is unsuccessful in catching the operating member.

Another object is to provide an automatic catching means for the operating member by which the operating member is returned to its inoperative position, in case the operator is unsuccessful in catching, ready to be released again in a succeeding operation.

Another object is to provide controlling means for the operating member.

Another object is to provide actuating means for the operating member.

Another object is to provide controlling means for the releasing member operative by the operating member if properly caught by the operator.

Another object is to provide handling means for the releasing member by which releasing members beyond a certain number in operation are automatically delivered into a storing compartment.

Another object is to provide a checking means by which unauthorized releasing members are prevented from going through the device.

Other objects will appear from the following description and appended claim as well as from the accompanying drawing, in which:

Fig. 1 is a front elevation of a game with a transparent front behind which certain operating and releasing members can be made to appear in front of a partition, to operate according to this invention.

Fig. 2 is a front elevation of the game from which the front and the partition have

been removed and also portions of certain operating parts, to facilitate an illustration of the principal operating mechanisms behind the partition.

Fig. 3 is a fragmentary cross section on line 3-3 of Fig. 2, illustrating the checking means for the releasing members in a slightly enlarged scale.

Fig. 4 is a fragmentary end elevation of the checking means in slightly enlarged scale.

Fig. 5 is a fragmentary top view of the control means for the operating member extending into the path of the releasing member to be actuated thereby.

Fig. 6 is a fragmentary top view of the actuating means for the operating member.

As illustrated, the frame structure 7 encloses a transparent front 8 and the partition 9 so that there is a space left between the transparent front and the partition.

The partition is set off to form a shoulder portion 10 on which a ball or similar suitable operating member 11 may run for operating purposes, the upper section 9_a being therefore set back further than the lower section 9_b of the partition with respect to the front 8.

Inasmuch as there is then a narrower space between the front 8 and the lower section 9_b, the releasing members 12, operating in this section or space between the lower section 9_b and the front 8, are preferably of a flat or narrower form.

The operating member 11 is intended and designed to come towards the front through the aperture 13, to run either towards the left or right over the incline-members 14_a or 14_b and further downward over the other incline-members 15_a or 15_b to drop over or from the furthermost edges of these members in the directions of the arrows 16, being intercepted and deflected in its downward fall by the pins 17, by which the course of the operating member is changed repeatedly and suddenly to such an extent that it requires a great deal of skill on the part of the operator to catch the operating member by the cup-like rearward projection 18 behind the figure 19 in order to win the game.

On a successful handling of the figure with 100

the cup, the operating member can be brought to a position to fall through the enlarged or aperture-like portion 20 of the slot 21. In this manner, on an unsuccessful handling of the figure 19 with the cup 18, the operating member 11 falls past the cup and figure upon the shoulder portion 10, to pass through the aperture 22 towards the rear, behind the partition, back into inoperative position.

Quite a number of releasing members, after passing into and through certain operating stages in this game-device, can be made to appear behind the transparent front 8 and before the lower section of the partition as indicated at 12.

In this retained position these releasing members are held by the wheel 23 which in turn is held in this retaining position by the pawl 24, preceding a discharge of the releasing members through the aperture 25 into the receiving cup 26, from which they may be picked up by the operator for successive or continued games.

A lever 27, disposed behind the partition 9, is, together with the pawl 24, mounted on a common shaft or pin 28, whereby the pawl, under the tension of the spring 29, or by means of gravity, is held in engaging position so as to hold the wheel 23 in retaining and inoperative position. The lever 27 is in operative connection with another lever 30 by means of the rod 31, the free end 32 of the lever 30 extending and projecting into the path indicated by the arrow 33 of the falling operating member when this operating member is discharged rearwardly through the enlarged or aperture-like portion 20 referred to above.

When the operating member 11 is successfully caught in the cup 18 behind the figure 19 and discharged through the portion 20 towards the rear behind the partition 9, the operating member 11 passes into the chute 34 in order to fall in the direction of the arrow 33 as stated above to come to rest in its inoperative position behind the catch 35, this being held stationary by the releasing lever 36, held in its engaging position by the spring 37.

The releasing lever can be disengaged from the catch 35 by a dropping of a releasing member 12 upon the pin 39 of the releasing lever 36, as may be better understood from the illustration jointly of Figs. 2 and 3.

A chute 38 is therefore arranged in such a manner as to bring a releasing member into proper position to drop on the pin 39. This chute 38 is in communication with the checking means roughly outlined at 40, by which a releasing member can be fed into the device in the direction of the arrow 41 as indicated in Figs. 1 and 2.

The checking means illustrated in Figs. 2 and 3, and 4 consists principally of the hingedly connected halves 42 and 43 between

which a releasing member can be deposited so as to roll through the chute 38 until the releasing member drops upon the pin 39 as and for the purpose described above. The halves of the checking means can be separated by the set-screw 44 along the lower edges 45 in such a manner that thinner or unauthorized releasing members will fall through. On the other hand, the adjustability of the halves serves to prevent the use of an overthick releasing member, since such a member will not roll or pass through the checking means in certain adjusted positions. A plunger 46 with the outwardly extending head 47 serves to release an overthick releasing member, however, and this device may be removed from the game device in order to eliminate unauthorized use of this.

The figure with the rearwardly extending cup is operative by a lever mechanism disposed back of the partition, the figure having a portion extending through the slot 21 and, being mounted on the slide member 48, shiftable on the guide-bars 49, the cup and figure alone being in front of the partition and behind the transparent front. The lever 50, in operative connection with the slide member 48, is mounted together with the lever 52 on a common shaft 51 and connected by the rod 53 to another lever 54, which in turn is mounted on a common shaft 55 together with the knob 56, which is on the outside of the whole device, as illustrated in Fig. 1, whereby the inside lever mechanism is controlled.

By a turning of the knob 56, the figure 19 with the rearwardly projecting cup 18 can be manipulated behind the transparent front 8 and before the partition 9 in such a manner as to enable a skillful operator to catch a downwardly passing operating member 11 even though this operating member may be interrupted and deflected by the pins 17 suddenly and quickly.

The figure 19 and the cup 18 being manipulated in the space between the front 8 and the partition 9 with the larger portion of the cup between the figure and the partition during the catching manipulations, the operating member 11, when properly caught in the cup 18, is held in this cup between the front and the partition unless and until the figure with the cup is brought to a point whereby the cup is coming into alignment with the enlarged or apertured portion 20, through which the operating member is able to slip or fall or roll, while the operating member is too large to pass through the slot 21, so that the operating member can not pass out of its caught position in the cup until the figure with the cup is manipulated to the discharging position before the enlarged portion 20.

When the operating member has been released from its inoperative position behind

the catch 35 by the tilting of the lever 36 when a releasing member drops on the pin 39, the operating member rolls in the chute 57 to the operative position at 58. From 5 this operative position the operating member is thrown or jerked or forced upwardly through the chute 59 in order to appear through the aperture 13 for the dropping and catching operation and manipulation 10 described above.

The lever 60, under the tension of the strong spring 61, serves to force the operating member upwardly. For actuating the lever 60, the pins 62 are disposed to come into 15 engagement with the lever 60 for moving the lever against the tension so as to increase the tension of the spring.

The pins 62, mounted on the cross piece 63 and therewith mounted, together with the 20 knob 65, on a common shaft 64, serve to actuate the lever 60 against the strong spring 61. The knob 65 is also mounted on the frame 7 as the knob 56 and the head 47 of the plunger 46, to be operated and manipulated from the 25 front of the whole device.

Any releasing member passed through this device in the manner stated above, upon hitting the pin 39 when falling through the chute 38 in that direction passes on through 30 the chute 66 which terminates in the partition 9 so that these falling releasing members pass through the aperture 67 in the partition to roll through the chute 68 as long as this chute is not filled, the furthermost releasing 35 member in this chute coming into contact and resting on one of the prongs 69 of the wheel 23. After the chute 68 is filled, the releasing members pass in the direction of the arrow 71 into a compartment within the whole 40 device behind the partition, while as long as the chute is not filled the releasing members may be said to pass in the direction of the arrow 70 into the chute 68.

The prongs 69 have a double purpose as 45 will be understood from the above, one being the holding of the releasing members in the chute 68, and, on the other hand, these prongs serve to hold the wheel 23 in its stationary releasable position by means of the pawl 24.

Certain of the prongs are shorter so that 50 they will easily pass the pawl 24, since the pawl by its interconnection with the lever 27 is held in a certain adjustable position by the screw 72; while others of the prongs are longer to always engage with the pawl 24. Under this arrangement, one, two, or more 55 releasing members can be discharged at a time, the releasing members in the chute 68 acting against the wheel 23 so as to turn it whenever the wheel is freed from the engagement with the pawl, depending on the number of short prongs between the longer 60 prongs.

When an operating member has not been 65 caught properly so as to gain the aperture 22,

it automatically passes towards the rear into its inoperative position below the end 32 of the lever 30 without touching or affecting the mechanism for releasing any releasing members from the chute 68.

In an unsuccessful manipulation of the figure, or after such an unsuccessful manipulation, a new releasing member will have to be inserted in to the checking device 40 in the direction of the arrow 41, since no releasing 75 member will be forthcoming or discharged from the lower aperture 25.

The aperture 22 in the partition is very close to the point where the operating member is normally located in its inoperative position so that the escaping operating member comes in the direct path to this inoperative position instead of in the direction of the arrow 33 through the chute 34.

Having thus described my invention I 85 claim:

In a game, in combination with releasing and operating members, a controlling means to form the support for the operating member in inoperative position, a pivotally disposed pawl in cooperative relation to said support with its free end extending down to a point to keep the operating member in such inoperative position, a chute for releasing members, a centrally pivotally supported lever with one end locking said pawl in inoperative position and with the other end disposed under said chute operative by a releasing member dropping upon it from the chute for releasing the said pawl so as to free the operating member to move to operative position, 100 a conduit, actuating means for forcing the operating member from said operative position through said conduit to dropping position, catching means adapted to be moved 105 to catch the operating member from the dropping position, a receiver for the used releasing member, a conduit to hold a number of received releasing members, a stop-rotor to hold the releasing members in 110 the last named conduit, a pawl-mechanism adapted at one end to hold said rotor locked against rotating movements and at the other end disposed so that the caught operating member will actuate the mechanism by dropping on this end and thereby adapted to release a predetermined number of said releasing members next to said rotor, and means for controlling the said catching means.

In testimony that I claim the foregoing as 115 my invention I have signed my name.

JOSEPH HEIDEMANN.
